UNITED STATES PATENT OFFICE.

CHARLES M. STEVENSON, OF ROCKFORD, ILLINOIS, ASSIGNOR TO IOWA GATE COMPANY, OF CEDAR FALLS, IOWA, A CORPORATION OF IOWA.

STALL CONSTRUCTION.

1,373,458.

Specification of Letters Patent.

Patented Apr. 5, 1921.

Application filed August 3, 1917. Serial No. 184,254.

To all whom it may concern:

Be it known that I, CHARLES M. STEVENSON, a citizen of the United States, residing at Rockford, in the county of Winnebago 5 and State of Illinois, have invented certain new and useful Improvements in Stall Constructions, of which the following is a description.

My invention belongs to that general class 10 of devices known as stall constructions, and relates particularly to a construction for making up a complete stall and carrying the stanchion, which is made up of a minimum of parts that may be easily and quickly installed. The invention has among its objects 15 the production of a stall construction of the kind described that is simple, convenient, compact, durable, efficient, ornamental and satisfactory for use wherever found applicable. It has particularly as an 20 object the production of a simple construction which may be manufactured and sold at low cost, and which may be installed by almost anyone. It has as a further object 25 the production of a combined support for the stanchion as well as combined partition, which parts are rigidly and securely held in place. Many other objects and advantages 30 of the construction herein described will be obvious to those skilled in the art from the disclosure herein made.

To this end my invention consists in the novel construction, arrangement and combination of parts herein shown and described, 35 and more particularly pointed out in the claims.

In the drawings, wherein like reference characters indicate like or corresponding parts,

40 Figure 1 is a side elevation of the partition member, cross bar shown in section.

Fig. 2 is a rear elevation of the same.

Fig. 3 is a view of a modified clamp.

Referring to the drawings, in which the 45 device is shown installed, 1 represents the stall floor and 2 the usual manger, which may be constructed in any desired manner. The stalls are made up of a series or plurality of units which are suitably connected 50 together, the number of units depending upon the number of stalls desired. Each unit consists of a part 3 forming substantially a leg, which is looped back as at 4, and thence extended downwardly and bent 55 at 5 to provide the rearwardly extending

partition 6, the free or rear end being turned down to form a leg 7 for the rear end of the partition. Each unit is preferably made up of an integral bar or pipe. The legs 3 and 7 may be secured in place on the floor or 60 curb in any desired manner, and therefore I have not considered it necessary to describe or illustrate in detail any particular construction herein. The several stall units described are connected by means of a top 65 or head bar 12 in any desired manner. In the construction shown I provide a bracket clamping part 8, which is secured to the unit by the U-bolts 9, or their equivalents for the purpose. The bracket part 8 is 70 formed to receive and support the bar 12, the same being secured in place by a coöperating clamping member 10 and bolts 11, or equivalent means for the purpose.

The looped construction is preferred, inasmuch as it enables the bar 12 to be placed in alinement with the vertical legs 3, so that when the stanchions are installed on bar 12 they will aline with the legs 3. A slightly modified form of clamp is shown 75 in Fig. 3, in which 18 and 20 represent the two clamping parts and 21 bolts which secure the clamp parts together with the partition bar 12 between the clamps, and at 80 the same time secure the clamps to the partition part 4' which corresponds to part 4 shown in Fig. 1. In this case two bolts are shown which extend through the partition and part 18, the nuts 19 securing part 18 on the bar. Obviously part 20 may be removed without removing the clamp part 18 85 from its support.

I have not considered it necessary herein to describe any particular form of stanchion or other fittings which may be employed, as 90 the stall herein shown is applicable for practically any style of stanchion and other fittings. It will be noted that there are no sharp corners or edges against which the stock may rub or become injured, and that 95 with the exception of the clamps 8-10, which are made as tight as possible, there are no recesses into which vermin can gain access. The stalls may be easily and quickly installed by almost anyone, without skilled 100 labor, and may be spaced and arranged as desired. With the exception of clamping the bars 12 in place, no coupling or threading of parts is necessary. It also has the 105 advantage that the units may be shipped 110

easily, as they may be packed together. It is also a simple matter to add additional units when it is desired to increase the stall capacity of the barn. The units may be shipped out with the brackets 8 locked in place, so that it is only necessary to secure the units in place, insert the pipe 12 through the clamps and tighten down the bolts 11 to set up the stalls.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:—

1. The combination of a plurality of similar units, each consisting of a partition bar bent down at each end to constitute supporting legs, the bend at one end at the juncture of the bar and leg constituting a semi-circular loop, a bar extending across said units at one of the ends thereof above the bent down leg at said loop, and means for rigidly fastening said units and bar together.

2. A stall comprising two similar partitions and a bar connecting said partitions, each partition bent upwardly at one end, and thence looped and bent downwardly to constitute a leg at the head end of the partition, and bent downwardly at the other end to constitute a relatively short leg at the rear end, and clamping means for securing said partitions and bar together adjacent the

upper ends of the legs at the front end and in alinement with the depending leg at the head end of the partition. Said clamping means mounted on said partitions.

3. In a stall of the kind described and in combination, a pair of similarly formed partitions, each consisting of a bar extended upwardly at one end, and thence looped back and extending downwardly to constitute a leg at the front end of the partition, the other end of each partition turned downwardly to constitute a short leg at the rear end of the partition, a clamp mounted on each stall partition at the loop therein substantially above the leg at the front end and a bar extending between the partitions and secured thereto by said clamp.

4. A stall comprising the combination of two side partitions, each consisting of a bar bent upwardly and laterally and thence looped and bent downwardly to provide a leg at the front end, and bent downwardly at the other end to provide a rear leg, said legs extending substantially parallel and one shorter than the other, a head bar extending across the partition bars above the long legs, and means for securing said head bar in place at a point in the loop between the upwardly extending portion and the downwardly extending leg.

In testimony whereof, I have hereunto signed my name in the presence of two subscribing witnesses.

CHARLES M. STEVENSON.
